UNITED STATES PATENT OFFICE.

ROBERT B. KERNOHAN AND MORGAN W. HALL, OF PITTSBURGH, PENNSYLVANIA.

FURNACE CHARGING.

Application filed November 8, 1922. Serial No. 599,647.

To all whom it may concern:

Be it known that we, ROBERT B. KERNOHAN and MORGAN W. HALL, residing at Pittsburgh, in the county of Allegheny and State of Pennsylvania, citizens of the United States, have invented or discovered certain new and useful Improvements in Furnace Charging, of which improvements the following is a specification.

10 Our invention relates to means for charging material into furnaces, and finds particular value when embodied in what we term a "dolomite gun". An open-hearth steel furnace is lined with mineral substance, ordinarily a mixture of specific minerals, among which is dolomite, with which the furnace charge reacts. Reaction takes place chiefly along the margin of the pool of molten charge as it lies in the furnace, and accordingly the consumption of the lining material is most rapid, the erosion is greatest, along that marginal line. It follows from this that in furnace operation it is desirable to replenish the supply of 25 lining mineral, particularly along the margin of the pool.

This is commonly done by manual labor. The doors of the furnace are opened from time to time, while furnace operation progresses, and attendants shovel the material, and throw it to the place desired. The work is arduous, the conditions under which it is done are most difficult to endure, and at best there is an element of inaccuracy in the placement of the material. Furthermore, the loose and more or less finely divided material so hurled across the furnace chamber meets the sweep of the gases of combustion, and the finer particles are in greater or less degree carried away on the stream of gases, and this with undesirable consequences: first, the material as it reaches its resting place on the back wall of the furnace, being deprived of an appreciable part 40 of its finer ingredients, does not consolidate as it should, and is therefore too rapidly consumed and wasted; and, second, the material carried on the stream of hot gases is in part deposited on the surface of the bath, where 45 its desired good effect is substantially lost, and in part carried beyond the furnace chamber and deposited in the checkwork of the regenerators, where it accumulates with manifest prejudice to furnace operation and 50 maintenance.

It has already been proposed to shoot

this material from a gun to its place on the furnace hearth, but the proposal has not overcome the difficulties alluded to, that the more finely divided particles of the injected material are swept away by the flame, and lost in the bath and lodged in the regenerators, while the coarser particles when they reach their resting place, do not themselves afford a sufficiently dense mass; and, in addition, it has been necessary to advance the muzzle of the gun into the furnace chamber and to a point adjacent the resting place for the material, and consequently there are difficulties incident to exposure of the apparatus to the heat of the furnace.

Our invention is found in a gun which projects the material in coherent units or charges which are not subject to deterioration in projection, and a gun which need not enter the furnace chamber.

The invention is illustrated in the accompanying drawings. Fig. I is a view in vertical and transverse section through an open hearth furnace, and showing in side elevation and in operative relative position adjacent the furnace, the gun in which our invention resides. The showing of Fig. I is diagrammatic. Fig. II is a similar view, but to larger scale, in which the showing of the furnace is but fragmentary, while the more minute structure of the gun is elaborated. Fig. III is a view in section of a detail, the plane of section being indicated by the line III—III, Fig. II. Fig. IV is a fragmentary view, illustrating a variation in the preparation of the material for introduction into and projection from the gun. Figs. V and VI are drawn to still larger scale, and together constitute a view in vertical and longitudinal section of a gun differing in detail from that of Figs. I—III.

Referring first to Fig. I, the furnace is indicated at 1. Its hearth 2 is formed of minerals of the nature indicated. Upon this hearth the furnace charge is melted and refined, and it is with the replenishing of the material of this hearth as it is consumed that our invention has to do. The door of the furnace is indicated at 3. The gun in which our invention centers is indicated at 4.

The gun will in any case be mounted in such manner that it may be moved about and brought to position opposite one or another furnace door, as may be desired. In the actual installation we are describing, tracks 5 are laid along the mill floor longi-

tudinally of the furnace, and upon these tracks a truck 6 is mounted to travel, which truck carries the gun. The arrangement is such that, as the car is moved along the tracks, the gun is advanced in position and brought opposite one or another of the doors 3 of the furnace.

In this Fig. I the dotted lines *a—a* indicate the trajectory of the material shot from the gun, and it will be observed that the material so shot will come to rest on what is called the back wall of the furnace, more specifically, on the hearth at the remote margin of the molten pool which constitutes the furnace charge.

Turning from Fig. I to Fig II, we come to more minute features of structure. The gun is here shown to be mounted upon the truck 6, through a vertical swivel 8 and a horizontal swivel 9, to the end that the gun may be aimed, and that the shot-in material may be placed on the back wall of the furnace high or low, to right or to left, as may be desired.

The truck 6 carries a tank 10 which, in operation, will be understood to be filled with air under compression. The truck may also carry a motor and a pump for compressing air, but since these features form no necessary part of our invention, they are not shown. From the tank 10 there is pneumatic communication to the barrel of the gun, to which in Fig. II the numeral 4 is immediately applied, and at the breech end thereof. This communication is controlled by a valve 11 operable manually, as is indicated. The port controlled by the valve is a port of large capacity, and the valve is adapted to be opened immediately to the full. Immediately to rearward of the gun barrel proper 4 is a loading chamber 16. This chamber is provided with a receiving hopper 12. The opening through the hopper into the loading chamber is controlled by gates 13 held normally closed by a spring 14, and these gates, when closed, form a substantially tight joint. The pneumatic communication which has already been mentioned is immediate to this loading chamber and through it to the barrel at the breech end. A pusher 17 is provided operable manually from the outside to advance a charge when once it has been introduced from the loading chamber into the gun barrel at the breech end.

A screen 15 may be provided to protect the attendant from the heat of or from the light of the furnace.

In Fig. II the charge which is shot by the gun into the furnace is indicated in two successive positions, at *b* and at *c*. The charge consists of the desired material in proper physical condition, held within a container adequate to effect the ends already indicated. The container is essen-

tially cylindrical in shape and is of such size that being filled, it will snugly fill the barrel of the gun and pass, under the pneumatic pressure provided, through the barrel and be projected from the muzzle with 70 suitable force.

We have found that a paper bag constitutes an adequate container and, as is indicated in Figure II, this paper bag is formed with both ends gathered and tied. Paper bags ordinarily available are rectangular at the bottom. By using a bag which is gathered and tied at both ends we make a package or charge which is truly cylindrical. The paper employed will be of sufficient toughness and resistance to hold together when the charge is fired and to hold the charge as it passes through the gaseous stream and across the furnace chamber to its place of lodging, where the paper container will be broken by impact and the paper will be burned, but not before it has served its purpose. Its consumption will have no appreciable effect upon the steel-refining process.

In Figure IV we have indicated an alternative form for the container. Here is shown within the barrel 4 of the gun a filled container *d*. It is gathered and tied at the forward end. At the 95 rear end it is closed in the manner usual in paper bag making, but has secured to it a cup *e* which ordinarily will be made of paper also. This cup is so positioned that it flares rearwardly and is of such 100 shape and size that its side walls closely engage the bore of the barrel 4.

The gates 13 close behind the package as it is introduced. When the package has come to the position shown at *b* in the loading chamber, the pusher 17 is advanced, and so the package is carried forward into the barrel of the gun proper in the position indicated at *c*, or it may be advanced until it lies wholly within the bore. As has been 110 explained, it is so proportioned that it fits snugly within the bore. If the package be formed, as is particularly illustrated in Figure IV, it is desirable that the package be so far advanced into the bore that the 115 walls of the cup *e* will bear upon the walls of the bore.

Operation will readily be understood. The material to be placed in the furnace is taken and made up into a package as 120 described. The package is introduced through the hopper 12, the gates 13 swinging aside, and comes to place in the loading chamber. It is then advanced by means of the pusher until it is entered into the bore 125 of the gun. The valve 11 may then be thrown wide open. The sudden rush of compressed air from tank 10 fills all the space to rearward of the package or charge *b* and drives it through the barrel 4 and 130

5 ejects it with sufficient force to carry it to its intended place. Of course, the gun will initially have been aimed, and the attendant will by experience known how to 50 aim it, in order to bring the material to rest at the desired point. The material of which 10 the container is formed, in this instance paper, is such that immediately on impact it will be destroyed, either by bursting or by burning or by both, and it will be such as to have no disturbing effect upon normal furnace operation.

The modification illustrated in Figs. V and VI will not require labored description. 15 The barrel of the gun is here marked 24, the muzzle end of it is shown in Fig. V and the breech end in Fig. VI. Within this barrel and upon a central stem 27 a scoop 25 with hollow stem 26 reciprocates telescopically. 20 The stem 26 at its rear end is enlarged to form a piston 31. This piston is held by a trigger 28 at the rear limit of reciprocation until the time for firing comes. A suitable hopper 30 forms an opening through which 25 access is had to the scoop 25 when the scoop is retracted for the purpose of charging. The parts being in the position shown in Figs. V and VI, the material within its 30 container, which as already has been said is preferably a paper bag, is deposited in scoop 25. It is of such size and shape that, when placed in the scoop, the loaded scoop will advance freely through the barrel of the gun. When the scoop has been loaded and 35 compressed air has been admitted to the breech end of the barrel of the gun to rearward of piston 31, the trigger 28 is tripped (as is done by the swinging of the hand lever 29), the piston is driven to the left (as seen 40 in Figure VI), and the laden scoop is thrust muzzleward to the limit of its range of movement. The charge which it carries is under acquired momentum projected from the muzzle of the gun, to effect the end de- 45 scribed.

The packaging of the material overcomes the difficulties described above, attendant on manual operation; furthermore, in so aggregating the material in coherent units, nicely

shaped to and filling the bore of the gun 50 (Fig. II), it becomes possible to shoot them to much greater distances than has been possible with guns shooting loose material. In consequence, it is not necessary to advance the gun and cause its muzzle to project 55 through the door and into the furnace chamber, and the difficulties otherwise to be overcome in protecting the gun from high temperature are avoided.

As is intimated at the beginning of this specification, the apparatus here particularly described as a "dolomite gun", for projecting into an open hearth furnace charges of material for repair and maintenance of the furnace lining, is applicable generally for 60 projecting desired material to particular points within a furnace chamber.

We claim as our invention:

1. The method herein described of replenishing a furnace lining which consists in projecting lining material across the furnace chamber in aggregated units inaccessible to the stream of gas through which they are projected. 70

2. A projectile adapted to be used in the replenishment of furnace linings which consists of a quantity of lining material in an aggregated unit inaccessible to the stream of gas through which it in service is projected, substantially as described. 75

3. A projectile adapted to be used in the replenishment of furnace lining which consists of a quantity of lining material enclosed within a destructible container. 80

4. A projectile adapted to be fired from a pneumatic gun into a furnace chamber, said projectile consisting of a quantity of loose mineral held within a destructible container, said container being provided posteriorly with a rearwardly flaring cup adapted to engage the bore of a gun. 85

In testimony whereof we have hereunto set our hands.

ROBERT B. KERNOHAN.
